HAIR CURLER

Max M. Newman, New York, N. Y.

Application June 20, 1945, Serial No. 600,467

2 Claims. (Cl. 132—33)

1

My invention relates to hair curlers and is particularly directed to hair curlers which initially support a hair pin and which effect an engagement between the hair pin and a curl of hair formed around a mandrel of the curler. A hair curler of this type is shown in U. S. Patent No. 2,321,931 of June 15, 1943, to Victor M. Newman.

In curlers of this type, means should be provided on the curler to firmly retain the hair pin so that displacement thereof is avoided while the curler elements are manipulated to form the curl. Such firm retention is also required when the engagement between the formed curl and the hair-pin is effected as otherwise the engagement may be incomplete or generally unsatisfactory. However, in attaining this objective, it is desirable to avoid limiting the utility of the curler to a specific type or size of hair pin since a wide variety of hair pins are conventionally used at present.

With the foregoing in mind, an object of this invention is to increase the utility of such a curler by permitting the utilization of hair pins of varied sizes and shapes without sacrificing the required firmness of retention referred to above.

Another object of this invention is to provide an efficient hair pin retaining structure which shall spread the hair pin to an extent where its engagement with a curl is rendered more positive particularly in respect to larger curls and stray hairs.

Another object of this invention is to simplify the operating procedure in forming curls while producing a curler of extreme structural simplicity in which considerable manufacturing economies are realized.

Another object of this invention is to provide improved means for disassociating the formed and pinned curl from the curler.

Other objects of my invention will be apparent from the following description it being understood that the above general statements of the objects of my invention are intended to explain and not to limit it in any manner.

Referring to the drawings:

Fig. 1 is a side view of the improved curler partly in section to illustrate internal construction.

Fig. 2 is a top view of the improved curler.

Fig. 3 is a side view, partly in section, illustrating the position of the hair pin carrier after the curl has been formed and pinned, and the hair pin carrier has been retracted.

Fig. 4 is an enlarged section along the line 4—4 of Fig. 2.

Fig. 5 is a section along the line 5—5 of Fig. 1.

Fig. 6 is a section along the line 6—6 of Fig. 1.

The support 10 and mandrel member 11 may be integral and may be formed of wood, plastic, metal, etc. The support 10 also functions as a

2

handhold member and is formed with a longitudinal groove 12 in which is disposed the wire 13. The wire 13 extends the length of groove 12 and is bent over and secured to the housing 10 at 14.

Telescoped over the wire 13 for sliding longitudinal movement in the groove 12 is the hollow hair pin carrier 15 which also functions as a clamp, retaining a lock of hair between itself and the mandrel member 11 in the initial step of the curling operation.

The hollow hair pin carrier 15 is bent upwardly to form a manual operating member 16 by which the hair pin carrier 15 can be slid over the wire 13 in its telescoping action. In order to permit such action, the hair pin carrier 15 is formed with an opening 17 through which the wire 14 enters the hollow of the hair pin carrier. The mandrel member 11 is formed with a longitudinally extending concavity 18 which communicates with the slot 12 thus providing a continuous path for the hair pin carrier 15.

The hair pin carrier 15 is tubular as seen in Fig. 4 and an arcuate section of its outer end is cut away to form a hair pin gripping tongue 19. This hair pin gripping tongue includes the hump 20 formed by bending the tongue 19, and the downwardly biased tip 21. Thus, the tongue 19 is substantially L-shaped by being bent in two directions, the hump 20 terminating one angle leg of the L while the tip 21 constitutes the other angle leg. It will further be noted that the tongue is of sufficiently small size and extent as to be substantially confined to the closed end of the hair pin. This not only permits wider opening of the hair pin but permits almost the entire hair pin to receive the curl. Tongue 19 cooperates with the cut edge 22 of the carrier 15 in gripping the hair pin 23. The hair pin which is of the conventional substantially U-shaped

construction has its lower leg 24 gripped between the tip 21 and the cut edge 22 thus relieving the tubular portion of the carrier 15 of this function. Accordingly the leg 24 is accorded the full diameter of the comparatively substantially wider carrier 15 as seen in Fig. 4, so that the thickness of the leg 24, or the fact that it may assume various shapes does not prevent its being received by the carrier 15. The edge 22 bears against one point of leg 24 and thereby urges

the leg against the opposite wall of the carrier 15. Thus plastic hairpins which are ordinarily thicker than metal hairpins can be accommodated. Additional retention plus spreading of the hair pin is effected by the tip 21 which co-

acts with the hump 20 in interposing an effective wedge between the leg 24 and the leg 25 of the hair pin. It will be observed that this wedge is disposed adjacent to the junction of the legs 24 and 25 so that the angle of spread is considerably increased. The downwardly biased tip

21 acts in opposition to the hump 20 in effecting the wedging action. With the foregoing construction, it may be considered that the hair pin is held at 4 places, viz., the major position of the leg 24 frictionally abutting the inner wall of the tubular carrier 15, the pressure of the cut edge 22 against the leg 24, the pressure of the tip 21 adjacent the junction of the legs 24 and 25, and the hump 20 acting in opposition thereto. The pressure at these distributed points avoids the necessity of a gripping element specifically shaped to fit the legs of the hair pin.

The mandrel 11 is little more than semi-circular in cross section as illustrated in Fig. 5, but at the inner end thereof its sides rise, as seen in Figs. 1 and 2, so that its overall thickness at the point adjacent the wire 13 is increased accordingly. One of the purposes of this increase in thickness is to prevent the formed curl from accompanying the hair pin carrier as it recedes into the groove 12 of the support 10 since the curl will have been formed around the lesser thickness of the mandrel member 11 and its internal diameter will therefore be such as to prevent it riding over the portion of increased thickness.

A ring 26 is slid over to mandrel member 11 and, making frictional contact with the larger diameter of support 10, serves to complete the assembly of the device and to prevent the complete disassociation of the hair pin carrier 15 from the telescoped wire 13 as seen in Figs. 1 and 2.

The simplicity of assembly of the instant device is notable. The wire 13 is initially inserted in place. The hair pin carrier 15 is then slid in from the opposite end until the opening 17 causes it to telescope the wire 13. The ring 26, which may be of metal, rubber or the like, is then slid over the mandrel member to the support where it is frictionally retained, completing the assembly.

My invention is practiced in the following manner:

The hair pin is applied to the mandrel member by inserting its leg 24 into the outer end of the tubular hair pin carrier 15 whereupon the above mentioned gripping elements take effect. A lock of hair is then applied between the hair pin carrier 15 and the mandrel member 11 where it is retained due to the tendency of the carrier 15 to maintain its position in the concavity 18. The device is then rotated so as to form a curl 27 around carrier 15 and mandrel member. The operating member 16 is then rearwardly actuated by the fingers thereby retracting the carrier 15 and the hair pin. This retraction continues until the hair pin is caused to embrace the curl 27.

During this retraction, the leg 24 of the hair pin is carried toward the wire 13 due to the telescoping action of the carrier 15 and said wire. When it approaches the groove 12 it will meet the stationary wire 13 as illustrated by the dotted lines of Fig. 3 so as to prevent further movement of the hair pin. Continued retraction of the carrier 15, therefore, necessarily disassociates the hair pin from the carrier gripping elements and effectively frees the formed and pinned curl. Any tendency of the curl 27 to enter the groove 12 is resisted by the increased diameter of support 10 at that point so that the formed curl is effectively prevented from entering the support and to this

extent, the increased diameter cooperates with the wire 13, each jointly serving to resist the continued movement of the respective hair pin and curl. This expedient further serves to maintain the degree of engagement between the hair pin and the curl during the ejection of the pinned curl from the curler.

During the retraction of the carrier, and after the tongue 19 leaves the closed end of the hair pin, the movement of the hair pin is confined to a straight path since it is guided by and rides in the concavity 18 of the mandrel member. Thus it cannot swerve so as to distort the curl or interfere with its proper pinning. When the carrier 15 is finally retracted, the hair pin is still in the concavity 18 and its lower leg is loosely held by the tongue 19 as illustrated in Fig. 3. This insures control of the curl at all times during its formation and pinning.

I have shown a preferred embodiment of my invention but it is obvious that numerous changes and omissions may be made without departure from its spirit.

I claim:

1. A hair pin curler comprising a mandrel member, a hair pin carrier, said hair pin carrier being slideable relative to said mandrel member and both being adapted to have a curl of hair formed jointly thereover, means on said hair pin carrier to receive one leg of a hair pin, said hair pin being carried by said carrier and being operative to engage said curl of hair as said carrier is slid relative to said mandrel member, means on said mandrel member to guide said hair pin in a predetermined path during its carriage by said carrier so as to prevent displacement of said curl during the travel thereof and stop means for intercepting said leg as said hair pin carrier is slid relative to said mandrel member whereby said hair pin is disassociated from said hair pin carrier, said hair pin guiding means comprising a concavity formed longitudinally of said mandrel member, said concavity serving to receive at least a portion of said hair pin so as to confine said hair pin to a predetermined path on said mandrel member during the travel of said hair pin.

2. A hair pin curler comprising a mandrel member, a hair pin carrier, said hair pin carrier being slideable relative to said mandrel member and both being adapted to have a curl of hair formed jointly thereover, means on said hair pin carrier to receive one leg of a hair pin, said hair pin being carried by said carrier and being operative to engage said curl of hair as said carrier is slid relative to said mandrel member, said hair pin carrier being round in cross section and said mandrel member being concavely arcuate adjacent said hair pin carrier whereby said hair pin carrier is received and embraced by said mandrel member.
